(57) **CLAIM**

The ornamental design for a chef's knives carrying case and working platform, as shown and described.

DESCRIPTION

FIG. 1 is a side isometric view showing the exterior of the chef's knives carrying case and work platform showing our new design;

FIG. 2 is side elevational view thereof showing the carrying case from one end and in a standing position;

FIG. 3 is an isometric view thereof in an open/flat position;

FIG. 4 is a top view thereof in an open position;

FIG. 5 is a bottom view thereof in an open position;

FIG. 6 is a sectional view thereof taken along line 6—6 of FIG. 1 in order to illustrate the interior; and,

FIG. 7 is an isometric view thereof showing the carrying case from the other end shown in FIG. 1 and in a standing position.

The dashed lines define stitching. The stitching also defines unclaimed pocket borders except for the stitching in the handle and except for the stitching in FIG. 5 and FIG. 6 that surrounds the stippled area.
